(57) **CLAIM**

The ornamental design for components for fishery demands, as shown and described.

DESCRIPTION

FIG. 1 is a front perspective view of a first embodiment of the present design for a component for fishery demands; FIG. 2 is a side view thereof, the front and rear views being identical;

FIG. 3 is a top view thereof;

FIG. 4 is a top perspective view of the present component for fishery demands;

FIG. 5 is a bottom view thereof;

FIG. 6 is a front perspective view of a second embodiment of the present component for fishery demands;

FIG. 7 is a side view thereof, the front and rear views being identical;

FIG. 8 is a top view thereof;

FIG. 9 is a top perspective view thereof; and,

FIG. 10 is a bottom view of the embodiment of FIG. 6.
